UNITED STATES PATENT OFFICE.

SAMUEL E. GUINN, OF JOHNSON CITY, TENNESSEE, ASSIGNOR TO S. E. GUINN MANUFACTURING CO., OF CINCINNATI, OHIO, A CORPORATION OF NEW YORK.

DESIGN FOR A COMBINED MATCH HOLDER AND ASH RECEIVER.

Application filed November 1, 1924. Serial No. 11,248. Term of patent 14 years.

To all whom it may concern:

Be it known that I, SAMUEL E. GUINN, a citizen of the United States, residing at Johnson City, in the county of Washington and State of Tennessee, have invented a new, original, and ornamental Design for a Combined Match Holder and Ash Receiver, of which the following is a specification, reference being had to the accompanying drawing, forming part thereof, and in which—

Fig. 1 is a perspective view of the combined match-holder and ash receiver.

Fig. 2 is a side elevation of the same.

I claim:—

The ornamental design for a combined match holder and ash receiver, as shown.

SAMUEL E. GUINN.
